UNITED STATES PATENT OFFICE.

THOMAS M. GALLAGHER, OF ST. LOUIS, MISSOURI, ASSIGNOR TO THE SHICKLE, HARRISON & HOWARD IRON COMPANY, OF SAME PLACE.

DESIGN FOR A CAR-BOLSTER.

SPECIFICATION forming part of Design No. 26,517, dated January 12, 1897.

Application filed November 2, 1896. Serial No. 610,886. Term of patent 14 years.

To all whom it may concern:

Be it known that I, THOMAS M. GALLAGHER, a citizen of the United States, residing at the city of St. Louis, in the State of Missouri, have 5 invented and produced a new and original Design for a Car-Bolster, of which the following is a description, reference being had to the accompanying drawing, forming part of this specification.

My invention relates to the design of a bolster-beam for railway-cars illustrated in the drawing, which is a perspective view.

The design consists of a rectangular body 1, having a downward swell 2 at the central

part of its lower surface and having at each 15 end and on each side a pair of ribs 3. The top surface of the body is flat, as illustrated in the drawing, and near each end of the body is a bracket or table 4. On top of the body, at the center thereof, there is a ring-like 20 bracket or table 5, having a base 6.

I claim as my invention—

The design for a car-bolster herein shown and described.

THOMAS M. GALLAGHER.

In presence of—

B. L. FREDERICK,
STANLEY STONER.
